(57) **CLAIM**

The design for a holder for liquid dispensers, as shown and described.

DESCRIPTION

FIG. 1 is a left, front perspective view of a holder for liquid dispensers in accordance with my design;
FIG. 2 is a front elevational view thereof;
FIG. 3 is a rear elevational view thereof;
FIG. 4 is a left side elevational view thereof;
FIG. 5 is a top plan view thereof;
FIG. 6 is a bottom view thereof;
FIG. 7 is an environmental, left, front perspective view thereof;
FIG. 8 is a rear elevational view thereof;
FIG. 9 is a front elevational view thereof; and,
FIG. 10 is a left side elevational view thereof.

The broken lines showing a liquid dispenser is for the purposes of illustrating environment and forms no part of the claimed design.
